US00D954122S

(12) **United States Design Patent** (10) Patent No.: **US D954,122 S**
Liu (45) Date of Patent: ** Jun. 7, 2022

(54) **TELESCOPE**

(71) Applicant: **Yaodong Liu**, Zhengzhou (CN)

D841,071 S 2/2019 Soejima
D846,014 S 4/2019 Sakai
D847,247 S 4/2019 Fischbach
D885,454 S * 5/2020 Liu D16/131

(72) Inventor: **Yaodong Liu**, Zhengzhou (CN)

* cited by examiner

(**) Term: **15 Years**

Primary Examiner — Holly E Thurman

(21) Appl. No.: **29/775,115**

(74) Attorney, Agent, or Firm — Rumit Ranjit Kanakia

(22) Filed: **Mar. 22, 2021**

(57) **CLAIM**

(51) LOC (13) Cl. **16-06**

The ornamental design for a telescope, as shown and described.

(52) U.S. Cl.

USPC **D16/133**

(58) **Field of Classification Search**

USPC D16/130-136

CPC G02B 23/16

FIG. 1 is a front elevational view of a telescope showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof;

FIG. 7 is a perspective view of a telescope showing my new design; and,

FIG. 8 is another perspective view thereof.

The broken lines in the figures are for the purposes of illustrating portions of the telescope, which form no part of the claimed design.
